[57] **CLAIM**

The ornamental design for a flip and blade antenna for radiotelephone, as shown and described.

DESCRIPTION

FIG. 1 is a perspective view of a flip and blade antenna showing our design in the environment of a radiotelephone; FIG. 2 is a side view thereof;

FIG. 3 is a top view thereof;

FIG. 4 is an opposing side view thereof;

FIG. 5 is an end view thereof;

FIG. 6 is an opposing end view thereof;

FIG. 7 is a top view of the flip and blade antenna alternately positioned;

FIG. 8 is a perspective view showing our design with the flip and blade antenna in an open position and on a reduced scale with respect to FIGS. 1-7;

FIG. 9 is a side view thereof;

FIG. 10 is a top view thereof;

FIG. 11 is an opposing side view thereof;

FIG. 12 is an end view thereof;

FIG. 13 is an end view illustrating the blade antenna alternately positioned relative to the flip; and,

FIG. 14 is a top view of the blade antenna in FIG. 13. The broken lines shown herein are for illustrative purposes only and form no part of the claimed design.
